(57) **CLAIM**

The ornamental design for a folding chair as shown and described.

DESCRIPTION

FIG. 1 is a right front perspective view from above of the folding chair showing my new design;

FIG. 2 is a right rear perspective view from below of the folding chair of FIG. 1;

FIG. 3 is a front elevational view of the folding chair of FIG. 1;

FIG. 4 is a rear elevational view of the folding chair of FIG. 1;

FIG. 5 is a top plan view of the folding chair of FIG. 1;

FIG. 6 is a bottom plan view of the folding chair of FIG. 1; and,

FIG. 7 is a right side elevational view of the folding chair of FIG. 1, the left side elevational view being a mirror image thereof.

The broken lines shown in the figures are for the purpose of illustrating portions of the folding chair and form no part of the claimed design.
